UNITED STATES PATENT OFFICE.

JOHN F. CAMERON, OF NEW YORK, N. Y.

SCRUBBING-MACHINE.

SPECIFICATION forming part of Letters Patent No. 311,810, dated February 3, 1885.

Application filed January 23, 1884. (No model.)

To all whom it may concern:

Be it known that I, JOHN F. CAMERON, a citizen of the United States, residing at New York, in the county of New York and State of New York, have invented certain new and useful Improvements in Scrubbing-Machines, of which the following is a description.

This invention relates to that class of scrubbing-machines which are mounted upon wheels, and which give to one or more scrubbing-brushes a reciprocating motion as they advance upon the floor.

The object of my invention is to provide means whereby water may be delivered to the exact point desired; means whereby a brush may be reciprocated to scrub the floor; means whereby the surplus dirty water may be gathered from the floor, and means whereby the same may be allowed to settle and the clear water be used again.

To this end my invention consists in the construction and combination of parts hereinafter described and claimed, reference being had to the accompanying drawings, in which—

Figure 1 is a side elevation, and Fig. 2 is a plan view, of my invention.

A represents the frame of the machine, mounted on four wheels, B, and provided with a handle, C, which may engage the frame at a to pull it by, or at b to push it by.

D is a shaft journaled in the frame, and provided with belt-pulleys E and cranks F. This shaft receives motion from two of the drive-wheels B by means of belts G G' and an intermediate speed-increasing pulley H.

I is the scrubbing-brush, made thin and flat to extend completely across the front end of the machine on the floor. It is perforated in several places, J, to let water pass down through it.

K K are rods connecting the brush with cranks F, whereby the brush is reciprocated upon the floor rapidly by the act of advancing the machine. The brush is held upon the floor by its own weight and the weight of rods K.

L is a tank to carry water.

M is a pipe leading from the tank, and provided with a sprinkler-head or nozzle, N, which is carried just ahead of the brush, and is provided with holes in the rear side of said nozzle to squirt the water against the front side of the brush, not only to supply water to wet

the floor, but to wash away mud that accumulates on the front side of the brush.

O is a wheel journaled in a yoke, P, which is hinged at Q to the main frame.

R R are two rollers journaled in arms f, which are hung upon the hinge-rod Q, and adjustably secured to the yoke P by means of the arcs g and binding-screws h, in order that the rollers may run on the floor and support the wheel and yoke, and in order that the yoke may be adjusted to the wear of the buckets.

S represents said buckets, made of flexible material—such as rubber—and secured to the wheel O in curves extending rearward from the ends to the middle of the wheel on its under side. This wheel is revolved by means of a crossed belt, T, running over a pulley, U, on one of the drive-wheels B. Wheel O revolves in the opposite direction to the drive-wheels, in order that it may sweep up the surplus water and the dirt therein as the machine advances.

V is a water-way hinged at its upper edge to drag its lower edge upon the floor. It is curved in a cylindrical arch tangent to the buckets S, in order that it may guide the water swept up by them into the settling-pan W. This pan is fixed to the frame of the machine at an angle slightly inclining forward, and it extends the whole length of the machine to give a broad area for the mud to settle out of the water. Its forward end is perforated above the bottom to allow the clear water to run out, and this front end is located above the brush, that the water may be again delivered at the point needed for use.

X X represent two water-guides, made of rubber, secured each in a head, and provided with a shank, Y, which is fitted tightly in the frame; yet it may be turned to give the rubber guide more or less inclination to the line of travel, and may be raised or lowered to set the rubber more or less firmly on the floor. The purpose of these guides is to turn the water on the floor into the path of the bucket-wheel, to be taken up thereby. The buckets of the wheel are curved to guide the water toward its center, to be carried up the way V with more certainty. The pipe M is provided with a cock, Z, by means of which the flow of water upon the brush may be regulated or stopped.

I am aware that scrubbing-machines have been patented showing reciprocating scrubbing-brushes, slanting settling-pans, means for raising dirty water from the floor into them, 5 and a revolving wheel having plane radial buckets; and I do not claim the same, broadly, as my invention.

What I claim as my invention, and wish to secure by Letters Patent, is—

- 10 1. In a scrubbing-machine mounted on wheels, having a brush hung at its forward end, and means for reciprocating the same, the combination of a pan hung to the machine and inclined forward, its forward end being above the said brush and perforated, and means, substantially as described, for raising water from the floor into the rear end of the said pan, as shown and described, whereby the same water may be brought forward of the brush and 15 used over again.
- 20 2. The combination, in a scrubbing-machine mounted on wheels, and having a settling-pan hung to it, of a wheel journaled in the machine across its rear end, having radial buckets 25 to wipe the floor, means for connecting the said bucket-wheel to the drive-wheel of the machine, with a water-way curved to the arc of the said buckets, and hung from the pan to the floor tangent to the said buckets, substan-

tially as shown and described, whereby water 30 may be wiped by the bucket-wheel from the floor all the way into the pan.

3. In a scrubbing-machine mounted on wheels, and having a settling-pan hung thereto, the combination of a curved water-way 35 hung to said pan to touch the floor, with a wheel having radial buckets curved backward from the edges to the center, and hung tangent to the said curved water-way, as shown and described.

4. The combination, in a scrubbing-machine mounted on wheels, of a settling-pan, a water-way leading thereto, a bucket-wheel, and side water-guides, and means for adjusting them, substantially as described, whereby they may 40 be set at any desired angle with the line of travel, and with any degree of pressure upon the floor.

5. The combination, in a scrubbing-machine mounted on wheels, of a settling-pan, a water-way leading thereto, a bucket-wheel journaled in a yoke hung by hinges to the frame of the machine, and independent rollers adjustably hung to said yoke, as shown and described.
